US00D561160S

(12) **United States Design Patent** (10) **Patent No.:** **US D561,160 S**
(45) **Date of Patent:** **** Feb. 5, 2008**

(54) **MOBILE PHONE**

(75) Inventor: **Henrik Jensfelt**, Limhamn (SE)

(73) Assignee: **Sony Ericsson Mobile Communications AB**, Lund (SE)

(**) Term: **14 Years**

(21) Appl. No.: **29/278,339**

(22) Filed: **Mar. 27, 2007**

(30) **Foreign Application Priority Data**

Oct. 30, 2006 (EM) 000613484-0001

(51) **LOC (8) Cl.** **14-03**

(52) **U.S. Cl.** **D14/138**

(58) **Field of Classification Search** D14/137-138, D14/147-148, 156, 218, 247-248, 341-347, D14/496; D16/208; D21/329, 331, 333, D21/517; 348/14.01-14.02; 361/814; 379/ 433.01-433.13; 455/90.3, 556.1-556.2, 455/566, 575.1, 575.3, 575.4

See application file for complete search history.

(57) **CLAIM**

The ornamental design for a mobile phone, as shown and described.

DESCRIPTION

FIG. 1 is a perspective view of a mobile phone showing my design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of environmental structures is for illustrative purposes only and forms no part of the claimed design.
